UNITED STATES PATENT OFFICE.

GEORGE W. WRIGHT, OF LAURINBURG, NORTH CAROLINA.

BURGLAR-TRAP.

SPECIFICATION forming part of Letters Patent No. 788,181, dated April 25, 1905.

Application filed October 8, 1904. Serial No. 227,759.

To all whom it may concern:

Be it known that I, GEORGE W. WRIGHT, a citizen of the United States, residing at Laurinburg, (R. F. D. No. 1,) in the county of Scotland and State of North Carolina, have invented a new and useful Burglar-Trap, of which the following is a specification.

The invention relates to improvements in burglar-traps.

10 The object of the present invention is to improve the construction of burglar-traps and to provide a simple and comparatively inexpensive one designed for use in banks, mercantile establishments, residences, and various other places and adapted to be conveniently arranged adjacent to a safe or at an entrance and capable of being automatically sprung by the weight of a person and of confining and locking the captured person to effectually prevent his escape.

15 A further object of the invention is to provide a trap of this character capable of being securely locked against operation to prevent it from being sprung during the day or other 25 desired time and adapted to be readily set when it is desired to arrange it for automatic operation.

20 The invention also has for its object to provide a burglar-trap which will be sprung only 30 when it is subjected to the greater portion of the weight of a person, whereby a person springing the trap will be prevented from escaping when he finds his supporting-surface giving away beneath his weight.

35 With these and other objects in view the invention consists in the construction and novel combination and arrangement of parts hereinafter fully described, illustrated in the accompanying drawings, and pointed out in the 40 claims hereto appended, it being understood that various changes in the form, proportion, size, and minor details of construction within the scope of the claims may be resorted to without departing from the spirit or sacrificing any of the advantages of the invention.

45 In the drawings, Figure 1 is a vertical sectional view of a burglar-trap constructed in accordance with this invention and shown set. Fig. 2 is a similar view taken at right angles 50 to Fig. 1. Fig. 3 is a vertical sectional view

similar to Fig. 1, showing the trap sprung. Fig. 4 is a horizontal sectional view. Fig. 5 is a detail view of the upper portion of the burglar-trap, illustrating the manner of locking the same out of operation. Fig. 6 is a detail view of one of the sliding frames.

55 Like numerals of reference designate corresponding parts in all the figures of the drawings.

1 designates a well or casing forming a cage 60 and adapted to receive a burglar or other intruder and extending downward from the floor or supporting-surface 2 a suitable distance. The well or casing, which may be constructed of any desired material, is preferably rectangular in horizontal section, and it receives a trap-door 3, which when the trap is set is arranged flush with the floor or supporting-surface 2. A suitable opening 4 is provided in the floor or supporting-surface to receive the 70 trap-door, which is guided in its downward movement by the well or casing. The trap-door, which is provided with arms 5 and 6, is connected by the means hereinafter described with a pair of sliding doors 7, mounted in suitable ways 8 beneath the floor and adapted 75 when the trap is sprung to cover the top of the well or casing for locking the captured person therein. The ways 8 are disposed horizontally and extend across the top of the well 80 or casing. The sliding doors are preferably provided at their ends with a spring-catch 9 or other suitable means for locking them in their closed position.

85 The arms 5 and 6 of the trap-door are formed by bars arranged at right angles to each other and suitably connected with the said trap-door. These arms, which guide the trap-door in its vertical movement, operate in slots or openings 10 and 11 of the sides of the well or 90 casing. The arms 5, which project in opposite directions from the trap-door, extend through the slots 10 and are adapted to engage slidable frames 12, which are connected at their tops by cables or ropes 13 or other 95 suitable flexible connections with the outer portion of the sliding doors. The slidable frames, which are substantially oblong, are composed of parallel rods and connecting top and bottom pieces 14 and 15. The rods are 100

- arranged in guides 16, and the lower connecting-piece 15 is substantially U-shaped, the upper terminals of the sides being bent outwardly and perforated to receive the rods. 5 The lower ends of the rods are threaded to receive nuts 17, which are arranged in pairs and which are located above and below the outer ends of the lower connecting-piece 15. The nuts enable the connections between the 10 trap-door and the slidable doors to be adjusted for closing the slidable doors properly when the trap is sprung. The connecting top piece 14, which is perforated to receive the outer ends of the rods, is also provided between the 15 same with a perforation for the adjacent end of the flexible connection 13. The flexible connection 13 is knotted or otherwise secured to the top piece 14, and the upper ends of the rods are preferably provided with heads, as 20 clearly shown in Fig. 6. When the slidable doors are open, the vertically-movable frames are raised and the lower connecting-pieces are arranged in the path of the arms 5, whereby when the trap is sprung the vertically-movable frames will be drawn downward for closing the sliding doors. Suitable guide-pulleys 13^a are arranged to receive the flexible connections, which extend from the slidable doors to the vertically-movable frames. 25
- 20 The trap-door is yieldingly held in its set position by means of a spring-actuated bolt 18, mounted in a suitable casing and having its engaging end beveled at the top and bottom and arranged in the path of a projecting keeper 19. The keeper is mounted on one of the arms 6, and the spring-actuated bolt, which may be of any desired construction, is designed to be of a strength sufficient to maintain the trap-door in a set position until the 35 40 said trap-door is subjected to a weight of about seventy-five pounds, or thereabout, so that the trap-door will not be sprung until it is subjected to the greater portion of the weight of an average person. This will prevent a burglar or other intruder from escaping when the trap is sprung and when he feels the supporting-surface giving away beneath him. 45
- The trap-door is positively locked in its set position by means of a pair of slidable bolts 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900
- of the well or casing and extending downward therefrom to the pulley 26 at that side of the trap-door. The setting rope or cable is then extended across the well or casing beneath the trap-door to the other pulley 26, 70 and its free end is supported by an upper guide-pulley 28. The guide-pulley 28, which is located at the side opposite that at which the setting rope or cable is fastened, is mounted in a suitable hanger, and the free end of 75 the rope or cable is arranged adjacent to one of the hinged trap-doors 25. By pulling on the rope or cable the vertically-movable trap-door may be elevated for setting the trap. When the vertically-movable trap-door is 80 raised by the setting rope or cable, the yieldable catch is adapted to automatically engage the projection or keeper of the arm 6 of the trap-door.
- It will be seen that the burglar-trap is simple and comparatively inexpensive in construction, that it is adapted to be readily constructed in various places, and that when set the trap-door forms a continuation of the floor and is not liable to arouse the suspicion 90 of the burglar or other intruder. Also it will be clear that when the trap-door is sprung the slidable doors will be automatically closed and will be locked in their closed position to effectually prevent the escape of a captured 95 person.
- Having thus fully described my invention, what I claim as new, and desire to secure by Letters Patent, is—
1. A device of the class described, comprising a well or casing, a vertically-movable trap-door operating within the well or casing, a device for yieldably supporting the trap-door at the top of the well or casing, means for closing the top of the well or casing when the trap is sprung, and connections between the trap-door and the said means for closing the latter. 100
  2. A device of the class described, comprising a well or casing, a vertically-movable trap-door operating in the well or casing, means for yieldably supporting the trap-door in an elevated position to set the same, slid- 110 able doors for closing the top of the well or casing when the trap is sprung, and means actuated by the trap-door for closing the slid- 115 able doors.
  3. A device of the class described, comprising a well or casing, a vertically-movable trap-door, means for closing the well or cas- 120 ing when the trap is sprung, and mechanism actuated by the trap-door for operating the said means.
  4. A device of the class described, comprising a well or casing, a trap-door, slid- 125 able doors for closing the well or casing when the trap is sprung, and means for setting the trap-door.
  5. A device of the class described, comprising a well or casing, a trap-door, means for 130

- setting the trap for the same, sliding doors for closing the well or casing when the trap-door is sprung, and means for closing the sliding doors.
- 5 6. A device of the class described, comprising a well or casing, a trap-door, slideable doors mounted at the top of the well or casing and separable to permit the trap-door to be arranged at the top of the said well or casing, and means for setting the trap-door, and means for closing the sliding doors when the trap-door is sprung.
- 15 7. A device of the class described, comprising a well or casing, a vertically-movable trap-door, a slideable door arranged at the top of the well or casing, a movable frame located in the path of the trap-door, and means for connecting the movable frame with the sliding door for closing the same when it is actuated by the trap-door.
- 25 8. A device of the class described, comprising a well or casing, a vertically-movable trap-door, slideable doors mounted at the top of the well or casing, movable frames arranged in the path of the trap-door, and flexible connections extending from the movable frames to the sliding doors.
- 35 9. A device of the class described, comprising a well or casing, a vertically-movable trap-door having opposite projections, oblong frames receiving the projections and arranged in the path of the same, sliding doors, and means for connecting the sliding doors with the said frames.
- 40 10. A device of the class described, comprising a well or casing, a vertically-movable trap-door provided with opposite projections, vertically-movable frames receiving the projections and arranged in the path of the same and composed of rods and upper and lower connecting-pieces, one of the connecting-pieces being adjustable, sliding doors, and means for connecting the sliding doors with the said frames.
- 45 11. A device of the class described, comprising a well or casing, a trap-door movable vertically from the top to the bottom of the well or casing, means for setting the trap-door, and a locking device for positively holding the trap-door in its set position at the top of the casing.
12. A device of the class described, comprising a well or casing, a vertically-movable trap-door, means for setting the trap-door, means for closing the well or casing when the trap-door is sprung, a locking device for positively holding the trap-door in its set position, and means for operating the locking device.
- 55 13. A device of the class described, comprising a well or casing, a vertically-movable trap-door provided with opposite pulleys, a setting rope or cable secured at one side of the well or casing and extending beneath the trap-door and received by the pulleys thereof, a guide-pulley arranged at the side opposite that at which the setting rope or cable is secured and receiving the free end of the same, and means for setting the trap-door.
- 60 14. A device of the class described, comprising a well or casing, a vertically-movable trap-door, a yieldable device for setting the trap-door, a slideable locking device having a loop and adapted to positively hold the trap-door in its set position, a fixed loop forming a fulcrum, and a removable bar or lever adapted to be placed in the fixed loop for engaging the loop of the slideable locking device.
- 70 15. A device of the class described, comprising a well or casing, a trap-door, means for setting the trap-door, slideable doors for closing the top of the well or casing when the trap-door is sprung, means operated by the trap-door for closing the sliding doors, and an automatic locking device arranged at the inner ends of the sliding doors when the latter are closed for securing the same in their closed position.
- In testimony that I claim the foregoing as my own I have hereto affixed my signature in the presence of two witnesses.
- GEORGE W. WRIGHT.
